UNITED STATES PATENT OFFICE.

GEORGE C. HALE, OF KANSAS CITY, MISSOURI.

LIFTING-JACK FOR AUTOMOBILES.

1,008,138.

Specification of Letters Patent.

Patented Nov. 7, 1911.

Application filed June 3, 1911. Serial No. 631,163.

To all whom it may concern:

Be it known that I, GEORGE C. HALE, a citizen of the United States, residing at Kansas City, in the county of Jackson and 5 State of Missouri, have invented certain new and useful Improvements in Lifting-Jacks for Automobiles; and I do hereby declare the following to be a full, clear, and exact description of the invention, such as will enable others skilled in the art to which it 10 appertains to make and use the same.

My invention relates to means for supporting automobiles when at rest, as, for instance, when they are standing in garages 15 or fire stations, so as to relieve the tires from the dead weight of the machine.

Experience has demonstrated that great damage results to the tires of automobiles from the constant weight of the machine 20 resting in one spot on said tires while the machine is not in operation.

It is the object of my invention to provide improved means for the purpose indicated.

25 Other objects are to facilitate the lifting of automobiles and the lowering and removal of the same from the supporting means when the machines are to be used.

My invention is particularly suitable for 30 use in fire stations or engine houses in connection with automobile fire apparatus.

The invention consists of a plurality of diaphragm lifting jacks adapted to be operated by fluid, under pressure, and connected 35 together to form a unitary structure adapted to fit below an automobile with one of the jacks positioned below the hub of each wheel. The frame connecting the jacks consists of pipes for supplying the actuating 40 fluid to said jacks. Said frame or system of pipes has a common inlet for the actuating fluid and a common relief valve whereby all of the jacks may be raised in unison and lowered simultaneously. Upright columns or 45 props are arranged upon each of the jacks for supporting the axles of the automobile.

These columns or props are capable of swinging down out of the way after the jacks are lowered and when the machine is 50 run out from above said jacks. Said props will automatically rise to upright position again as soon as released by the axles.

The invention also consists in the features 55 of construction and combinations of parts hereinafter described, illustrated in the ac-

companying drawing, and specified in the appended claims.

In the accompanying drawing: Figure 1 is a plan view of my lifting and supporting apparatus. Fig. 2 is a transverse vertical section taken centrally of two of the jacks and showing the axle of an automobile in its raised position with its wheels off of the floor, and Fig. 3 is a broken side view of the upper end of one of the columns or props 60 illustrating how it engages the axle, the latter being shown in cross section.

Referring more particularly to the drawing, 1 designates the main longitudinal pipe for conveying the actuating fluid to the jacks 2 which are connected to said main pipe by branch pipes 3. One end of said longitudinal pipe is closed, as at 4, its other end being equipped with a hose coupling 5 and a relief valve 6. Each of the jacks is round and flat 70 in form with a solid diaphragm 7 clamped firmly between its lower and upper flanges 8 and 9, respectively, by bolts 10, making a water and air tight joint around the edge of the jack. The inlet passage 11, into which 75 the pipe 3 is fitted, opens on the base of the chamber 12 in the jack below the diaphragm. The normal lowered position of said diaphragm is concave, as illustrated in dotted lines in Fig. 2. Its raised position is convex, as shown in solid lines. Said diaphragm may be made of any suitable flexible material possessing the necessary wearing properties. I have illustrated the diaphragm as composed of an upper disk 7^a of 80 heavy canvas and a lower disk 7^b of rubber bearing against the bottom of said upper disk. The rubber serves to prevent any leakage through the canvas and the latter is made sufficiently strong to withstand the 85 pressure of the actuating fluid.

A piston 13 is arranged above the diaphragm and is fitted in a short cylinder 14 formed integral with the upper flange 8 and having a ledge 15 for limiting the upward 90 movement of said piston. The under surface of the piston is preferably made concave to conform to the convex upper surface of the diaphragm when the latter is raised. A circular upwardly projecting rim 16 is 95 formed concentrically on the upper surface of the piston for the purpose of seating the lower end of the column or prop 17.

The props or columns may be made of wood, metal, or any other suitable material 100 110

but preferably consist of wooden shanks 17^a and upper and lower metal caps or ferrules 17^b and 17^c, respectively, and illustrated in Fig. 2. The upper caps 17^b are forked, as at 5 18, for engaging the axle 19 of an automobile. It is preferable to have the props engage the axle as near to the hubs 20 of the wheels 21 as practicable, but in order to bring the jacks within the wheel base of the 10 machine, so as not to interfere with the ready removal of the latter, said props are usually positioned at points on the axle below which the truss rod 22 extends. I, therefore, make deep forks or bifurcations 15 in the upper ends of the props so as to reach around the truss rod and engage the axle, as illustrated in Fig. 3. The wooden shank of each of the props is hollow and through it extends a helical spring 23 connected at its opposite ends to bosses 24 and 25, respectively, formed on the cap 17^b and the center of the piston 13. The ferrule 17^c on the lower end of the prop is, of course, perforated to correspond to the passage 25 through the shank. The inner wall of the rim 16 is rounded, as at 16^a, so as to permit the prop to swing down in any direction. The spring serves to automatically raise the prop to upright position when released.

30 When my invention is to be used, an automobile is run in over the device and stopped in position with its axles directly above the forward and rear pairs of jacks, respectively. The props are then adjusted below the axles, 35 by swinging said props laterally to clear the truss rods, and the actuating fluid admitted to the pipe 1 via the coupling 5 whereby the pistons of the jacks are raised by the diaphragms into the positions illustrated in 40 Fig. 2. The raising of the pistons elevates the axle through the medium of the props or columns 17 until the weight of the machine is removed from the tires on its wheels. When it is desired to use the automobile, the 45 relief valve 6 is opened, by any suitable means, liberating the fluid in the jacks. As soon as the pressure of said fluid is removed from below the diaphragms, they will drop to the positions illustrated in dotted lines in 50 Fig. 2, thereby lowering the axle of the automobile until the latter is supported upon its wheels. The dropping of the diaphragm, and of the pistons, of course, with them, removes the weight from the props or columns 55 which swing down out of the way as the automobile is run out.

I am aware that various changes may be made over the construction shown and described herein without departing from the 60 spirit or sacrificing the advantages of my invention. I, therefore, reserve the right to make such changes as fairly fall within the scope of the appended claims. It is also evident that water under pressure, steam or 65 compressed air may be used as the actuating

fluid for my lifting and supporting device. The fact that water, under the pressure in the ordinary city main, may be utilized, makes my invention especially suitable for use in fire stations or engine houses where 70 automobile fire apparatus is kept.

I claim:

1. In a lifting jack, the combination, with a lower chambered member, of a vertical cylinder, a piston mounted in said cylinder, 75 a prop seated upon said piston, means for yieldingly holding said prop in upright position, but permitting it to be swung down when required, and means to admit an actuating fluid into the chamber below the 80 piston.

2. In a lifting jack, the combination, with a lower chambered member, of a vertical cylinder, a piston mounted in said cylinder, 85 a prop seated upon said piston, means for yieldingly holding said prop normally in upright position, but permitting it to be swung down when required, means to center the lower end of the prop on the piston, and means to admit an actuating fluid into the 90 chamber below the piston.

3. In a lifting jack, the combination, with a lower chambered member, of a vertical cylinder, a piston mounted in said cylinder, 95 a prop seated upon said piston, means for yieldingly holding said prop normally in upright position, but permitting it to be swung down when required, a concentric rim having an outwardly and upwardly receding inner wall for the purpose specified, 100 and means to admit an actuating fluid into the chamber below the piston.

4. In a lifting jack, the combination, with a lower chambered member, of a vertical cylinder, a piston mounted in said cylinder, 105 means to admit an actuating fluid into the chamber below the piston, a prop mounted on the piston, said prop comprising a shank, having a longitudinal passage therein, a cap on the upper end of said shank, a perforated 110 ferrule on the lower end of said shank, a flexible connection extending through the passage in the shank and connected to the piston and to said cap, and means to center the prop upon the piston.

5. In a lifting jack, the combination, with a lower chambered member, of a vertical cylinder, a diaphragm arranged between said lower member and cylinder, a piston mounted in said cylinder above the diaphragm, a prop seated upon said piston, means for yieldingly holding said prop normally in upright position but permitting it to be swung down when required, and means to admit an actuating fluid into the chamber below the diaphragm.

6. In a lifting jack, the combination, with a lower chambered member, of a vertical cylinder, a diaphragm arranged between said lower member and cylinder, a piston 130

mounted in said cylinder above the dia-
phragm, a prop seated upon said piston,
means for yieldingly holding said prop nor-
mally in upright position but permitting it
5 to be swung down when required, means to
center the lower end of the prop on the
piston, and means to admit an actuating
fluid into the chamber below the diaphragm.

7. In a lifting jack, the combination, with
10 a lower chambered member, of a vertical cyl-
inder, a diaphragm arranged between said
lower member and cylinder, a piston mounted
in said cylinder above the diaphragm, a
prop seated upon said piston, means for
15 yieldingly holding said prop normally in up-
right position but permitting it to be swung
down when required, a concentric rim hav-
ing an upwardly and outwardly receding
inner wall for the purpose specified, and
20 means to admit an actuating fluid into the
chamber below the diaphragm.

8. In a lifting jack, the combination, with

a lower chambered member, of a vertical cyl-
inder, a diaphragm arranged between said
lower member and cylinder, a piston mounted
25 in said cylinder above the diaphragm,
means to admit an actuating fluid into the
chamber below the diaphragm for raising
the piston, a prop mounted on the piston,
said prop comprising a shank having a lon-
30 gitudinal passage therein, a cap on the upper
end of said shank, a perforated ferrule on
the lower end of said shank, flexible connec-
tion extending through the passage in the
shank and connected to the piston and to
35 said cap, and means to center the prop upon
the piston.

In testimony whereof, I affix my signa-
ture, in presence of two witnesses.

GEORGE C. HALE.
